UNITED STATES PATENT OFFICE

2,183,069

EYELETING MACHINE

Sylvester L. Gookin, Quincy, Mass., assignor to
 United Shoe Machinery Corporation, Borough
 of Flemington, N. J., a corporation of New
 Jersey

Application June 30, 1939, Serial No. 282,211

2 Claims. (Cl. 218—15)

This invention relates to eyeletting machines and more particularly to raceways as used in such machines to supply eyelets having oblong barrels to a spindle of corresponding shape carried by one of the eyelet-setting tools. The eyelets illustrated herein have barrels of oval cross-section and the invention is intended to provide for handling not only eyelets of that type but also eyelets having barrels of rectangular oblong 5 shape.

In providing shoe uppers with oblong eyelets for the lacings, it has heretofore been the practice to arrange such eyelets in the relation illustrated, for example, in United States Letters 15 Patent 1,722,286, granted July 30, 1929, on my application. According to the disclosure in that patent, the major diameters of the eyelet barrels lie in a line parallel with the adjacent edge of the upper over which the lacing is intended to 20 extend, but a demand has now arisen for an eyeletting machine that will place the eyelets so that their major diameters will lie at right angles to the lacing edge of the upper.

In all former raceways for handling oblong 25 eyelets the eyelet-guiding channels have open delivery ends through which the eyelets may be removed only with movement in the direction of their major diameter, in some cases with, and in others without, means for turning the eyelets to 30 place their major diameters in the direction required for their removal. However, if a raceway is of the type that requires sidewise reciprocation, and the major diameter of the eyelet-spindle is parallel with the movement of the race- 35 way, the eyelet lodged on the spindle will not be in the position desired for its insertion into the work according to present requirements.

Consequently, an object of the present invention is to provide a raceway of the type that may 40 be operated with sidewise reciprocation to supply oblong eyelets to an oblong spindle of which the major diameter lies at right-angles to the lines of reciprocation of the raceway. The expression "oblong eyelets" is intended to characterize the cross-sectional shape of the barrels of 45 the eyelets without regard to the shapes of the eyelet flanges and is intended to include both oval and rectangular oblong shapes.

The raceway illustrated herein is like former 50 raceways in that its eyelet-guiding strips are spaced according to the minor diameter of oblong barrels, wherefore the major diameters of the barrels are maintained approximately parallel with their path of travel therein, but the 55 raceway differs from prior raceways in that its

delivery end is closed but has provisions for removal of oblong eyelets from one side thereof while the major diameters of the eyelets lie at right-angles to the lines of reciprocation of the delivery end. For this purpose a wide notch is 5 formed in one side of the raceway to clear the spindle, and herein lies the problem of maintaining control of the eyelet at the delivery end.

The width of the notch must exceed the major 10 diameter of the spindle, and the flange of the eyelet must bridge the notch. The provision of a notch of large enough dimensions leaves so little supporting surface for the flange of the eyelet that other means are required to prevent the eyelet from tipping and falling through the 15 notch.

To satisfy this requirement the invention provides a spring-biased member arranged to guide the leading eyelet in the raceway across the notch by engagement with a major side of the barrel. 20 This guiding member is, in effect, an extension of the guiding strip that terminates at the notch to clear the spindle, and although it projects only part way across the notch, its extent of projection is enough to maintain the barrel up- 25 right until the flange of the eyelet bridges the notch and finds support at the opposite side thereof. The eyelet is thus prevented from tipping as it slides across the notch. Another spring-biased member located at the opposite 30 side of the notch projects toward the one first-mentioned, each of them partially closing the gap through which the eyelet barrel is finally removed, and both of them being effective to maintain the eyelet in spindle-receiving position. 35

Referring to the drawings,

Fig. 1 is a top plan view of the delivery and of a raceway constructed in accordance with this invention, the view also including an eyelet-inserting tool to which the eyelets are to be supplied;

Fig. 2 is a cross-sectional view indicated by line II—II in Fig. 1;

Fig. 3 is a side elevation of the delivery end of the raceway as viewed from the left;

Fig. 4 is a perspective view of a portion of an eyeletting machine of the type more fully illustrated in United States Letters Patent 1,722,286 and particularly the raceway-operating mechanism thereof; and

Fig. 5 represents a typical example of work such as a quarter of a shoe upper in which oblong eyelets have been inserted in accordance with the provisions of the raceway illustrated herein.

The raceway is designed to be mounted and operated according to Fig. 1 in the patent above-mentioned, which figure is reproduced in the present drawings as Fig. 4 with appropriate changes such as the substitution of the new type of raceway, a corresponding arrangement of the setting tools, and omission of certain parts not necessary for the purposes of the present disclosure. The raceway assemblage has provisions for mounting it on the left-hand side of the frame 13 to which it is connected by a vertical fulcrum pin 11. This mounting enables the delivery end of the raceway to be reciprocated sideways in lines indicated by arrow A in Fig. 1, its movement to the left serving to carry an eyelet into register with the spindle 12 of an eyelet-inserting tool 13, and its movement in the opposite direction serving to remove the eyelet from the raceway and to clear the path of the tool 13. As shown in Fig. 1, the spindle 12 and the barrels 14 of the two eyelets are of oval cross-section.

The raceway comprises a base plate 15 and two cooperative eyelet-guiding strips 16 and 17 mounted thereon but spaced therefrom as usual in such constructions. The guiding edges of the strips are spaced one from the other in accordance with the minor diameter of the oblong barrels 14. The arrow B represents the direction in which the eyelets travel in the raceway. A notch 20 is formed in the base plate 15 to receive the spindle 12 and its open end is at the left to permit the raceway to move to the right after delivering an eyelet to the spindle. Considering the side 21 of the notch as the high side because the eyelets approach the notch from that side, the guiding strip 16 is terminated at the high side but the strip 17 is longer to guide the eyelets across the notch. The flanges of the eyelets are seated on the base plate 15 and the barrels extend upwardly therefrom. The eyelets are adequately controlled by the strips 16 and 17 until they reach the high side 21 of the notch, but since the eyelets must slide a considerable distance beyond the end of the strip 16, the latter is not effective to keep the flanges of the eyelets on the ledge 27 of the base plate as shown in Fig. 2 or to maintain the barrels 14 upright. It is therefore necessary to provide other means to maintain these conditions as the eyelets slide across the notch, for if they are permitted to tip or slide to the left, they will fall through the notch.

Consequently, to insure adequate support and control of the eyelets at this point, the raceway is provided with a spring-biased member 22, the eyelet-engaging portion 23 of which is more clearly shown in Fig. 2. This portion 23 lies on the upper surface of the shorter strip 16 and serves, in effect, as an extension thereof, although it projects only part way across the notch 20. Its extent of projection is sufficient, however, to maintain the flanges of the eyelets on the ledge 27 and to maintain the barrels 14 upright until the leading edges of the eyelets have crossed the notch and become lodged on the base plate at the far side of the notch, as illustrated in Fig. 3.

The spring-biased member 22 spans the strip 17 and is seated upon the base plate 15 to which it is connected by a pivot stud 24. The spring bias is provided by a light tension spring 25 one end of which is engaged with a hole in the member 22 and the other end of which is engaged in a hole in an ear 26 formed on or affixed to the base plate. As represented in Fig. 1, the eyelet-engaging extremity of the member 22 is broken away

to avoid obscuring the high side 21 of the notch; but the normal position of the portion broken away is represented by dotted lines. A stop 24 is provided to prevent the eyelet-engaging portion 23 from being projected too far across the notch 20.

When an eyelet has advanced to a position in register with the notch 20, its barrel is arrested by a stop 30 which, as shown in Fig. 1, is provided by a shoulder formed at the delivery end of the guiding strip 17. Turning movement and escape of the eyelet at this point are prevented by the tip of a spring-biased member 31 that projects part way across the notch 20 toward the portion 23 of the member 22. The gap between the tips 15 of the members 22 and 31 is slightly less than the major diameter of an oblong barrel 14 (see Fig. 3) but an eyelet once lodged as last described can be removed from the raceway by the spindle 12 when the raceway is moved to the right. The barrel 14 then forces the members 22 and 31 away from each other, but they close the gap before the next eyelet in the raceway requires their control. The member 31 is seated on the base plate 15 and connected thereto by a pivot stud 32. A compression spring 33 maintains it normally in the position shown in Figs. 1 and 3.

When an eyeleting machine of the type illustrated in the patent above-mentioned is equipped with a raceway constructed in accordance with this invention and with oblong eyelet-setting tools correspondingly arranged, it will insert the eyelets in the relation pictured in Fig. 5. In this figure 34 represents a portion of a shoe quarter 35 and 35 is the lacing edge thereof. The major diameters of the eyelets lie at right angles to the edge 35. This edge is the one by which the work is guided while the machine is in operation.

Referring to Fig. 4, the eyelet-inserting tool 13 is affixed to the upper end of a vertical bar 36 that inserts the eyelets with upward movement, the operation of the bar being derived from a power-driven camshaft 38 through the medium of a lever 39.

A horizontal work-supporting table indicated at 40 is provided with an edge-gage 41 and with a hardened steel punch-block 42. A combined punch and setting tool 43, of oval shape corresponding to that of the tool 13, is carried by an upper bar 44 to which vertical reciprocation and sidewise reciprocation are imparted by coordinated mechanisms not shown herein but which produce a four-way motion of the tool 43; viz., first, a downward motion against the punch-block; second, a sidewise work-feeding motion to the left which places the tool 43 in alignment with the tool 13; third, upward movement to retract the tool 43 from a clenched eyelet; and fourth, a sidewise movement to the right to complete the cycle. The tool 43 dwells at the completion of its work-feeding stroke while the lower tool 13 inserts an eyelet and clenches it.

The raceway is affixed to a carrier 45 and this carrier is the element connected to the frame 10 by the vertical fulcrum pin 11. The motion for reciprocating the delivery end of the raceway sideways is derived from a cam 46 carried by the shaft 38 and is communicated to the forward end of the carrier 45 by a train of connections comprising a lever 48, a link 49, a bell-crank lever 50, and a link 51. The lever 48 is suspended from a horizontal fulcrum 47 but the bell-crank lever 50 is mounted on a vertical fulcrum.

Since oblong eyelets are used only for visible

eyeleting and since machines of the type herein disclosed are organized to insert the eyelets below rather than above the work, the operator places the lining of a shoe quarter uppermost for this kind of work.

Having described my invention, what I claim as new and desire to secure by Letters Patent of the United States is:

1. An eyeleting machine comprising cooperative eyelet-setting tools of oblong shape one of which includes a spindle of corresponding shape, a raceway the delivery end of which is movable crosswise of the major diameter of said spindle, said raceway having a base plate to support eyelets and cooperative eyelet-guiding strips spaced according to the minor diameter of oblong barrels and said base plate having a notch to receive said spindle, one of said strips terminating at the high side of said notch but the other extending past the closed end of the notch, two opposed spring-biased members carried by the raceway one of which is arranged to guide the eyelets across said notch to the other member by engagement with their barrels, and means by which

said delivery end is reciprocated to present and discharge the eyelets with movements crosswise of their major diameters.

2. A raceway for oblong eyelets comprising a base plate having a spindle-receiving notch at its delivery end of a width corresponding to the major diameter of oblong barrels, cooperative eyelet-guiding strips spaced according to the minor diameter of the barrels and arranged to conduct the eyelets to said notch with crosswise approach thereto, one of said flanges terminating at the high side of the notch but the other extending past the closed end of the notch, and two spring-biased members carried by the raceway and having eyelet-engaging portions projecting toward each other from opposite sides of said notch, one of said members having a barrel-guiding portion in line with the barrel-guiding edge of the shorter of said strips to maintain the barrels upright as the eyelets slide across said notch, the eyelet-engaging portions of said members being separable by an eyelet removed widthwise between them.

SYLVESTER L. GOOKIN.
